UNITED STATES PATENT OFFICE.

CLARK NOBLE WISNER, OF NEW ORLEANS, LOUISIANA, ASSIGNOR TO C. N. WISNER
COTTON PICKER COMPANY, INCORPORATED, OF NEW ORLEANS, LOUISIANA.

PICKER-HEAD.

1,322,987.

Specification of Letters Patent. Patented Nov. 25, 1919.

Application filed May 27, 1918. Serial No. 236,713.

To all whom it may concern:

Be it known that I, CLARK NOBLE WISNER, a citizen of the United States, and a resident of New Orleans, in the parish of Orleans 5 and State of Louisiana, have invented certain new and useful Improvements in Picker-Heads; and I do hereby declare the following to be a full, clear, and exact description of the invention, such as will enable others skilled in the art to which it 10 appertains to make and use the same.

This invention relates to improvements in cotton pickers and more particularly to an improved picker head,—the object of the 15 invention being to so construct a picker head as to enhance its efficiency in removing cotton from the bolls.

With this and other objects in view, the invention consists in certain novel features 20 of construction and combinations of parts as hereinafter set forth and pointed out in the claims.

In the accompanying drawings; Figure 1 is an end view (partly broken away) of a 25 picker head embodying my improvements; Fig. 2 is a transverse sectional view; Fig. 3 is a longitudinal sectional view; Fig. 4 is a detail view showing the pin carrier and operating shaft, and Fig. 5 is an inside face 30 view of one of the end plates.

My improved picker head comprises a revoluble cylinder 1 disposed between two end plates 2, 3 connected by rods 4, 5, 6, and said end plates are provided in their inner 35 faces with annular grooves 7 in which said cylinder is mounted to turn. By thus mounting the cylinder in annular grooves in the end plates, cotton will be prevented from clogging between the ends of the cylinder 40 and said end plates. The end plates are made with circular portions or extensions 8 which constitute means for supporting a tube 9 having a slot 10 to receive cotton from the picking means carried by 45 the cylinder, as hereinafter explained. The tube leading from any suitable pneumatic means (not shown) will be connected with the tube 9 and if the latter be extended beyond one of the end plates of the picker 50 head, it may serve as a handle.

An operating shaft 11 passes through the cylinder 1 and through suitable holes 12 in the end plates, suitable antifriction bearing devices 13 being provided on the respective end plates for said shaft and the latter

is extended beyond its bearing on one of the end plates for connection with suitable driving means. Rods 14 pass transversely through the cylinder and the shaft 11 and are rigidly secured at their respective ends 60 to the cylinder wall. The rods 14 serve not only to secure the shaft 11 to the cylinder 1, but also as guides for a carrier 15 having lateral flanges 16. A set of picker pins 17 projects from each flange of the carrier and 65 the pins pass freely through holes in the wall of the cylinder, the two sets of pins projecting from the carrier, respectively in opposite directions.

The body of the frame or carrier 15 may 70 be made cylindrical in form and is provided at respective ends with pairs of lugs or projections 15^a to receive between them circular cams 18 projecting inwardly from the end plates 2 and 3, so that when the shaft 11 and cylinder 1 are rotated, the carrier 15 will be caused to reciprocate within the cylinder 75 and cause the respective sets of picker pins to be alternately projected and withdrawn.

A hood 18^a is secured to the connecting 80 rod 4 and projects partly over the cylinder 1 some distance from the same, said hood being prevented from upward displacement by means of lugs 19 secured to the end plates 2, 3. The hood is also provided with 85 a flange 20 projecting downwardly toward the slotted receiving tube 9.

Curved guard fingers 21 are secured at 90 their lower ends to the connecting rod 5 and extend partly around the cylinder 1. 95 Those portions of the guard fingers 21 which are disposed in front of that portion of the cylinder which is presented to the cotton boll are caused to pass through portions of circumferential grooves 22 in the 95 cylinder, so that the picker pins will not be prevented by said guard fingers from effectively reaching the cotton in the boll. The upper portions 23 of the guard fingers bear 100 a tangential relation to the cylinder, projecting rearwardly in a slanting direction and terminating at their free ends below the upper portion of hood 18^a.

It will be seen that when the shaft 11 and cylinder 1 are rotated, one set of picker pins 105 will be projected as they approach the forward portion of the head and remove the cotton from the boll. As this set of pins approaches the upper portion of the head, the same will begin to recede and the slant- 110

ing upper portions of the guard fingers will strip the cotton bolls from the pins. By terminating the free ends of the guard fingers opposite to the top of the hood 18^a, the cotton will be permitted to pass freely under said hood, without liability of clogging or winding on said guard fingers, and will pass freely into the slotted receiving tube 9,—from which latter it may be withdrawn by 10 pneumatic means, as will be readily understood.

In order to obviate the possibility of the boll being moved aside by the picker pins without properly picking the cotton therefrom, an abutment rod 24 is provided and is disposed over the front of the head somewhat beyond the paths of the picker pins. The abutment rod is provided at one end with an arm 25 mounted in lugs 26 on the 15 end plate 2 and is held yieldingly in position by a spring 27,—a stop 28 being provided on said arm to engage the end plate to prevent said abutment rod from moving forwardly beyond its normal position. During 20 the operation of the picker head, the picker pins will engage the cotton in the boll and move the latter against the abutment rod 24. As the picker pins continue to move forwardly, the cotton will be withdrawn from 25 the boll and the abutment rod will yield to permit the remainder of the boll to readily slide off the same,—after which the abutment rod will again assume its normal position.

30 Having fully described my invention what I claim as new and desire to secure by Letters-Patent, is:—

1. In a picker head, the combination with 35 a frame, a hood thereon, picker pins, and 40 means for operating the latter, of a plurality of guard fingers disposed in position to strip the cotton from the picker pins, the upper portions of said guard fingers terminating below the upper portion of said hood, leav-

ing an open space between said guard fingers and said hood. 45

2. In a picker head, the combination with a frame, a hood thereon, a cylinder mounted in said frame and having circumferential grooves, picker pins projecting through 50 the wall of said cylinder, and means for operating said cylinder and picker pins, of a plurality of guard fingers secured to the frame and partially embracing said cylinder, portions of said guard fingers passing 55 through portions of the circumferential grooves in the cylinder, and the upper portions of said guard fingers projecting tangentially from the cylinder and terminating below the upper portion of said hood leaving 60 an open space between the guard fingers and hood.

3. In a picker head, the combination with a frame, picker pins, and means for operating 65 said picker pins, of a yielding abutment rod attached to the picker head and projecting over the path of said picker pins.

4. In a picker head, the combination with a frame comprising end plates and connecting rods, a cylinder mounted between said 70 plates, picker pins carried by said cylinder, and means for rotating the cylinder and operating the picker pins, of an abutment rod disposed in front of the paths of the picker pins, said rod having an arm rev- 75 olubly mounted on one of the end plates, and a spring connected with said arm permitting the abutment rod to yield in one direction, and a stop for limiting movement of said rod in the other direction. 80

In testimony whereof, I have signed this specification in the presence of two subscribing witnesses.

CLARK NOBLE WISNER.
